UNITED STATES PATENT OFFICE.

ELЛИCK H. GOLLINGS, OF LEWISTON, IDAHO, ASSIGNOR TO THE GOLLINGS BI-CENTRIC PUMP COMPANY, OF CHICAGO, ILLINOIS.

ROTARY PUMP.

SPECIFICATION forming part of Letters Patent No. 448,334, dated March 17, 1891.

Application filed March 1, 1889. Serial No. 301,675. (No model.)

To all whom it may concern:

Be it known that I, ELЛИCK H. GOLLINGS, a citizen of the United States, residing in Lewiston, in the county of Nez Perces and Territory of Idaho, have invented a new and useful Improvement in Rotary Pumps, of which the following is a specification.

This invention is intended to provide a construction in rotary pumps by which they will 10 be rendered more effective for the elevation of water to considerable heights, and by which the water will be discharged in a constant stream practically devoid of pulsations. I employ in its construction a suitably-supported non-rotating shaft which is hollow at both ends, one end serving as an inlet-passage for the water and the other as a discharge or outlet passage. Upon this shaft is concentrically mounted a rotary shell or hollow 15 wheel. Both water-passages in the shaft have lateral ports within this shell and on opposite sides of the shaft. Within the central part of the shell and between the ports is a wheel of smaller diameter than the interior 20 of the shell, having radially-partitioned chambers or water-spaces and mounted upon an eccentric portion of the same shaft that carries the shell. This wheel is mechanically connected with the shell in such manner as 25 to rotate with the same number of revolutions in a given time and at a practically uniform rate of speed, while it has an independent eccentric movement within the shell. By reason of this uniform rotary speed of the eccentric-wheel the stream discharged by the pump 30 is substantially uniform and is deprived of those pulsations and irregularities which are observed in the streams discharged by rotary pumps generally. The eccentric-wheel may 35 be, and preferably is, a rimless one composed of a series of wings, which are prolonged by hinged vanes of the same width as the wings themselves. In the eccentric movement of the inclosed wheel the free ends of these 40 vanes preserve contact with the interior periphery of the shell, and they therefore serve to successively enlarge and contract the water-spaces within the wheel, which spaces they in part inclose. In the preferred form of construction herein illustrated the spaces of the 45 eccentric-wheel are open at both sides of the

latter, and the shell is also divided at each side of the wheel into a series of chambers or pockets by radial partitions corresponding in number with the wings of the eccentric-wheel. 55 These chambers of the shell are open to receive and discharge directly from and into the shaft-passages, while they also communicate directly with the interspaces of the eccentric-wheel. Said chambers or partitions 60 of the shell, however, do not extend outwardly from the shaft beyond the hinges of the vanes, the end plates of the shell exterior to said hinges being parallel and continuous. Said shell-partitions desirably do not bear 65 upon the shaft, except where the latter is provided with longitudinal ribs at opposite sides of the shaft and at the opposite sides of the ports or passages which give communication from the interior of the shaft 70 to the interior of the shell. The width of each of these ribs is such that at all times some one of the partitions will be in contact with it, one partition moving to or over each rib as soon as or before the preceding 75 partition has passed beyond it. These ribs are in the same plane with each other and in the same plane with the longest throw of the eccentric, and the driving connections between the shell and wheel are so arranged 80 that the wings of the eccentric-wheel and the partitions of the shell will coincide with each other on both sides of the shaft in this same plane of the longest throw of the eccentric. By this construction and arrangement the 85 interior of the shell, including the interspaces of the eccentric-wheel contained therein, is divided into two parts in the plane of the axes of the wheel and eccentric-wheel, one of said parts being in communication with one 90 port of the shaft and the other part in communication with the other port of said shaft. By the rotation of the shell and its contained wheel the separate chambers in one of these parts will expand or be enlarged progressively 95 from the beginning to the end of their semicircular movement, and in their following semicircular movement in the other half of their revolution they will progressively contract. By such progressive enlargement they 100 allow the water or other liquid being pumped to enter them, and by their subsequent pro-

gressive contraction they operate to expel the water. That port which is connected with the half of the shell-space in which the chambers progressively expand will be the inlet-port 5 and the other will be the outlet-port. In order to rotate the inclosed eccentric-wheel by rotation of the shell and to give it the same number of rotations and a practically uniform speed, a series of projections are provided on the wheel, which successively engage one at a time with suitable surfaces on the shell, such engagement in the case of each projection taking place outside the plane of division above pointed out or outside the 15 plane of the throw of the eccentric. To obtain the greatest uniformity of rotative speed between the shell and wheel, the driving engagement referred to should take place, and is herein shown to take place, in a short arc 20 midway of the half-circle cut off by said plane of greatest eccentricity, for the reason that the arc of contact (nearly a plane) is then practically parallel with the plane of greatest eccentricity, and the point of contact on the 25 shell is therefore at practically the same distance from the center of the shell as the point of contact on the wheel is from the center of the wheel. With this construction of the shaft, shell, and eccentric-wheel, and with the 30 resulting uniform or substantially uniform speed of the eccentric-wheel having the same number of rotations as the shell, a constant flow or stream will be produced which will be free from pulsations and unsteadiness.

35 The essential features of my pump are fully disclosed by the accompanying drawings, in which two forms of construction are illustrated.

In said drawings, Figures 1 to 4, inclusive, 40 illustrate one form of my invention. Fig. 1 is a vertical cross-section showing the interior of one-half the shell with the eccentric-wheel in position therein. Fig. 2 is a longitudinal vertical section on the line 2-2 of Fig. 45 1. Fig. 3 is a section similar to Fig. 2 upon line 3-3 of Fig. 1, and Fig. 4 is a cross-section similar to Fig. 1 with the eccentric-wheel removed. Figs. 1^a, 2^a, 3^a, and 4^a are views similar to the preceding, but illustrating a modified construction.

50 First describing the construction illustrated in Figs. 1 to 4, inclusive, A represents a stationary frame having supports *a*, one at either end, by which the non-rotating shaft *B* is upheld. This shaft is shown made of an integral piece, hollow at either end to provide water-ways, the passage *b* at one end being the water-inlet and the passage *b'* at the other end being the outlet on the assumption that 55 the rotation of the shell and its contained wheel is from left to right of Figs. 1 and 4. Between these passages *b* *b'* the shaft *B* is solid or closed, as indicated at *b*². Ports *b*³ *b*⁴ lead from said passages, respectively, to the interior of the shell on opposite sides of the shaft 60 and on different sides of the eccentric-wheel. 65

C are two parts or end plates of the

shell. They are provided with marginal flanges *c* to receive bolts, as shown, for joining the parts together, and each half of the shell 70 has a bearing, as *c'*, upon the shaft *B*. The shell is confined longitudinally upon the shaft by collars *b*⁵, one at either end of the shell, said collars being screw-threaded upon the shaft *B*, so as to be adjustable toward and 75 from the shell and being held from rotation by set-screws *a'* in the arm *a*² of the frame. Packing may be employed in the several bearings of the shell upon the shaft, as indicated at *a*³. The central portion of each part 80 *C* of the shell is made concavo-convex in form, as shown in Figs. 2 and 3, and the interior of this portion of each end of the shell is divided into a series of chambers or pockets *d* *d'* by partitions *D* *D'*, located in radial 85 planes and separated by spaces next the shaft *B*. The ports *b*³ and *b*⁴ are located abreast of these chambers, so that the feed-port discharges directly into the chambers *d* and the delivery-port receives directly from the chambers *d'*. At each side of each port *b*³ and *b*⁴ 90 the shaft is provided with a longitudinal rib *H*, of suitable width to extend from one partition to the next, so that one partition is always in contact at its inner edge with said rib. The ribs *H* are on diametrically-opposite sides of the shaft *B*, and are all in the same plane of the greatest throw of the eccentric. While passing these ribs the partitions 95 of the shell form practically water-tight joints 100 with them.

The eccentric-wheel within the shell is composed of a series of radial wings *E*, projecting from a hub *e*, said partitions corresponding in number with the partitions *D* *D'* in 105 each end of the shell, and, like said partitions, being separated by equal spaces. The eccentric-wheel is shown as having a two-part bushing *e'*, which embraces the eccentric portion *b*² of the shaft *B*, which bushing rotates with 110 the wheel, thus giving a reduced eccentric-journal upon which the wheel turns. To the outer end of each wing *E* of the eccentric-wheel is hinged a vane *F*. The hinge, as shown, consists of a transverse socket *f* in 115 the end of the wing, into which the parti-cylindric edge of the vane is inserted. The sockets *f* are preferably open at the sides of the wings to allow the vanes to be slipped into them sidewise. The free ends of the vanes *F* are held in close contact with the inner periphery of the shell by means of pins *f'*, which project laterally from the vanes and enter slots *f*² in the adjacent face or faces of the shell. For the radial space occupied by these 120 vanes *F* the inner faces of the parts *C* of the shell are parallel and closed or continuous. The slots *f*² are elongated to allow the eccentric movement of the wheel, in which movement the pins *f'* move constantly from 125 end to end of the slots. The vanes incline over the radial water-spaces *g*, formed between the wings *E* of the eccentric-wheel, and 130 are in effect yielding extensions of said wings,

moving inward and outward with respect to the wheel under the control of the eccentric upon which said wheel rotates. The spaces g of the eccentric-wheel form the communicating passages between the chambers $d d'$ of the shell, there being a passage or space g for each pair of opposite chambers $d d'$. The partitions $D D'$ of the shell and the wings E of the eccentric-wheel are of even number, so that one partition or one wing on one side of the axis of the shell or wheel is in line with a partition or wing on the opposite side. The driving connections by which the interior eccentric-wheel is driven from the shell are so located that two opposite partitions at each end of the shell will coincide with opposite wings of the eccentric-wheel in the plane of the greatest throw of the eccentric and in the plane of the ribs $H H$, so that there shall be a longitudinal division of the entire space within the shell into two parts, one of which communicates with the inlet-port of the shaft and the other with the outlet-port of said shaft.

In the construction shown in Figs. 1 to 4 the driving connection between the shell and wheel consists of the pins f' , projecting from the vanes F and working in the slots f^2 , as above described. When these pins and slots are relied upon to carry the eccentric-wheel with the shell in the rotary movement of the latter, some one of the pins will always be in bearing against the back end of the corresponding slot, and the eccentric-wheel will thus be pushed by the shell. To locate the slots properly to drive the wheel and to give the desired coincidence to the wings and partitions, as above set forth, in the plane of greatest eccentricity of said wheel, the wheel and shell are first placed with the partitions and wings coincident in said plane, and a pin is selected outside of said plane, (preferably the pin most remote from it,) for which a slot is laid out to bear at its rear end against said pin. After this slot is located the others are located at equal distances from each other in a circle concentric with the axis of the shell, and of course the slots will correspond in number with the pins on the vanes, so as to afford one slot for each pin. Each pin and slot will have driving contact at the selected point in each revolution of the shell, and said pins will therefore act singly and in succession to give rotary motion to the eccentric-wheel. The inner or eccentric wheel, being connected with the shell by hinged vanes and pins, as above described, will manifestly make the same number of revolutions as the shell and have practically a uniform speed, by reason of the large number of said pins all acting successively through the same short arc of contact. By reason of such uniform speed of the shell and wheel not only is a steady and pulseless flow of water produced, but the friction between the surfaces of the two rotating parts in contact is reduced to a minimum, the friction

actually present being only such as results from the eccentricity of the inner wheel. Another advantage of the simultaneous and uniform rotation of the wheel and shell is that at all points where these two parts are in contact the friction is the same and the wear is consequently the same or is uniform throughout the entire structure. The shell may be driven by means of an external rack m or otherwise.

In the construction described, in which the partitions $D D'$ and the wings E are made to coincide in the plane of greatest throw of the eccentric, the interior of the shell is divided into two parts cut off from each other, but communicating one with the inlet-port and the other with the outlet-port of the shaft B . In the rotation of the shell and wheel the chambers or water-spaces within the shell and wheel are severally expanded during their half-circular movement on that side on which they communicate with the outlet-port. As a consequence water is admitted to one part of said shell and wheel while it is being expelled from the other.

In the modification shown at Figs. 1^a, 2^a, 3^a, and 4^a the radial partitions of the shell are omitted, the eccentric-wheel is closed at the sides, (except that ports are formed near the axis,) and the shaft is provided with parti-annular flanges, one at either side of the wheel and on opposite sides of the shaft, each of which flanges closes one-half of such axial ports of the eccentric-wheel. Referring to these figures, in which I have, so far as possible, employed the same letters of reference as are used upon the other figures, the shaft is shown made in parts, the end portions B' being separate from the middle portion and the latter being also made in parts, one of which B^2 is the axis of the eccentric, corresponding to the part b^2 of the previous construction, another B^3 the portion in which is formed the inlet-port b^3 , and still another B^4 the part in which is formed the outlet-port b^4 . The shell is shown provided with annular enlargements M and N , affording spaces which surround the ports B^3 and B^4 , as shown clearly in Figs. 2^a and 3^a. The eccentric-wheel in this modified construction is formed with two side walls $g' g'$, laterally inclosing the radial spaces g , and it is also shown as having a rim uniting the two sides $g' g'$, which is provided with water-passages g^2 , giving communication of said spaces with the surrounding space of the shell. These radial spaces g also communicate with the spaces M and N within the shell through passages or ports i near the axis of the wheel. Half of the ports i are at all times closed by one of the stationary flanges J , and the other half on the opposite side of the wheel are at the same time closed by the other of said stationary flanges. These flanges are for this purpose made to overlap each other at their ends, so that no one space in the eccentric-wheel can at the same time communicate with the spaces M and N . They thus

perform the same function as the ribs H H, in connection with the partitions D D', of the construction shown in the preceding figures of the drawings.

- 5 The eccentric-wheel in the figures now being described is provided with vanes or yielding extensions F, essentially like those already described; but, not being relied upon for driving the eccentric-wheel from the shell, 10 the free ends of said vanes are held in contact with the inner periphery of the shell by projections at the ends of the said vanes, which run in a continuous groove p in the shell adjacent to the periphery of the shell. To cause 15 the rotation of the eccentric with and by the shell in this modified construction, I have shown pins s, projecting from the side of the eccentric-wheel into circular recesses s', larger than the diameter of the pins and located in 20 the abutting side of the shell. This enlarged and circular form of the recesses s' is necessary, because every part of the eccentric-wheel performs a circular motion with respect to an abutting surface of the shell, the radius of 25 such circular motion being equal to the throw of the eccentric. The diameter of these recesses s' must therefore be at least double the radius of the eccentric plus the diameter of the pin p. Theoretically and with accurate construction providing for simultaneous contact 30 of all the pins with the walls of the recesses one-half the number of pins and recess-surfaces will obviously be concerned in driving the wheel from the shell; but after wear or in 35 the absence of such accurate construction one after another of these pins serves to give the driving connection between the wheel and the shell, as already described, of the pins upon the vanes working in the slots, as illustrated. 40 in the preceding figures of the drawings. To locate the recesses s' or the pins p in the modified construction, the eccentric-wheel is first brought into such a position that the parti-annular flanges J will severally fully 45 close a series of the ports i, and after the first recess or pin is located the others are given position at equal distances therefrom in lines concentric severally with the wheel or shell.

Certain features of construction shown in 50 Figs. 1^a, 2^a, 3^a, and 4^a are made the subjects of claims in another application for patent, Serial No. 333,767, pending simultaneously with this. The shell in this modified construction fits closely against the closed sides 55 of the wheel, as clearly illustrated.

The capacity of the pump may be varied by increasing or diminishing the width of the eccentric-wheel or by increasing or diminishing the eccentricity or by varying the diameters of the parts, the inlet and outlet ports or 60 passages being correspondingly varied.

I claim as my invention—

1. The combination of a shaft having an eccentric portion, a shell with a cylindric chamber surrounding the eccentric portion of the shaft and concentric with the concentric portion of said shaft, said chamber having a se- 65

ries of inlet and outlet passages surrounding the shaft, a wheel mounted within the shell upon the eccentric portion of the shaft, a series of parts crossing the space between the wheel and the surrounding shell and successively forming a division of said space substantially in the plane of the eccentric, a series of driving connections engaging the shell 70 with the wheel, whereby one of these members is rotated by and with the other, said series of driving connections acting successively outside the plane of division, and means for admitting and discharging a fluid to and 75 from the passages on opposite sides of the division of the space between the shell and wheel.

2. In a rotary pump, the combination, with a stationary shaft provided with an eccentric portion and having interior passages at its ends opening on opposite sides of the shaft, of a rotating shell supported on the concentric portions of the shaft and covering said ports or openings, a wheel mounted on the eccentric portion of the shaft and provided with radial spaces extending through it, which are successively enlarged and contracted in the rotation of the wheel, a changeable part of the spaces in the eccentric-wheel being in communication with the inlet-port of the shaft and the other changeable part of the spaces being in communication with the outside of said shaft, and means for driving the said eccentric-wheel at a practically uniform 90 speed with the shell and at the same number of revolutions in a given time as the shell, substantially as described.

3. The combination, with a shaft having an eccentric portion, of a rotating shell mounted upon the concentric portion of the shaft, a wheel mounted within the shell upon the eccentric portion of the shaft, said wheel having radially-divided spaces which are successively enlarged and contracted in the rotation of said wheel, separated passages within the shaft, having ports on opposite sides thereof within the shell, means for cutting off communication of each of said ports with a changeable part of the spaces within the eccentric-wheel while giving communication of the same port with another and changeable part of said spaces, and a series of successively-engaging projections by which the eccentric-wheel is driven by the shell at a practically uniform rate of speed and at the same 110 number of revolutions within a given time as said shell, substantially as described.

4. In a rotary pump, the combination of a rotating shell, an eccentric-wheel within the shell, provided with a series of chambers radially divided by extensible partitions extending to the inner periphery of the shell, the space within the shell being divided into separated parts upon a substantially fixed 125 plane, which is that of greatest eccentricity, two axial passages, one communicating with one of said parts of the space embraced by the shell and the other with the other, and 130

means for driving the eccentric-wheel from and at the same rate of speed as the shell, substantially as described.

5. The combination, with the non-rotating shaft, the rotating shell, and the rotating eccentric and chambered wheel, of a series of driving-projections on one of the rotating parts engaging surfaces upon the other singly and in succession, said projections making such engagement outside the plane of greatest eccentricity of the wheel-axis.

6. The combination of a non-rotating shaft, a rotating shell mounted concentrically upon the shaft and provided at each end with a series of radially-partitioned chambers surrounding the shaft and opening both toward the shaft and toward each other, an eccentric-wheel within the shell, having a series of radially-partitioned spaces corresponding in number with the chambers at either end of the shell and open at both sides and also toward the periphery of the shell, yielding extensions of the partitions which separate the chambers of the eccentric-wheel and which prolong said partitions to the periphery of the shell, and driving connections by which the eccentric-wheel is driven from the shell at the same speed, the shaft being provided with axial passages opening on opposite sides of the shaft and in communication with separated groups of shell-chambers, substantially as described.

7. In a rotary pump, a rotating shell receiving and discharging the fluid at its ends, in combination with an eccentrically-mounted wheel located in and rotated by and in unison with the shell and dividing the same centrally, said wheel having variable passages open at its sides, and said shell being divided longitudinally at each end, substantially as set forth.

8. In a rotary pump, the combination of a rotating shell and an eccentric-wheel, rotating with the shell and filling the center thereof, a feed-passage opening into said shell at one side of the wheel, and a discharge-passage leading therefrom at the other side of said wheel, said wheel having passages variable in capacity, which are open to receive and discharge the fluid at the sides of the wheel, and the shell being divided longitudinally at each side of the wheel, substantially as specified.

9. The combination, with the shaft having passages and ports, as set forth, of a rotating hollow shell inclosing said ports and a rotating winged eccentric-wheel carrying movable vanes, essentially as described, the shell being divided by radial partitions at either side of the eccentric-wheel, substantially as described.

10. The combination, with the shaft having passages and ports, as specified, of a rotating hollow shell inclosing said ports and a rotating winged eccentric-wheel carrying vanes, essentially as described, the shell being divided into chambers at either side of the wheel by equally-spaced partitions agreeing in number with the equally-spaced wings of the eccentric and forming close joints therewith, substantially as set forth.

11. The shaft having passages and ports, as specified, and also having longitudinal ribs H, in combination with the partitioned shell and the eccentric winged wheel rotating on the shaft, the partitions of the shell forming close joints with the ribs H as they pass the latter, substantially as set forth.

12. The combination, with the shaft having feed and discharge passages and ports at opposite sides, of a rotating hollow shell inclosing said ports, and a rotating eccentric winged wheel dividing the interior of the shell and carrying inclined pivoted vanes which are mechanically held against the inner surface of the shell, substantially as set forth.

13. The combination, with the shaft having the passages and ports, as specified, of a rotating hollow shell inclosing said ports, and a rotating winged eccentric-wheel, the wings whereof carry vanes expanding and contracting, as set forth, and extending over the spaces between the wings, said vanes having pins working in slots in the shell, substantially as set forth.

14. The combination, with the shaft having the feed and discharge passages and ports at opposite sides, of the hollow chambered rotating shell and the eccentric winged wheel inclosed within and rotating with the shell and having peripheral vanes, substantially as set forth.

15. The combination of a shaft having an eccentric portion and a concentric portion, a rotating shell mounted on the concentric portion of the shaft, a rotating wheel mounted on the eccentric portion of the shaft, and a series of radially-movable parts connected with the shell and having contact with its inner periphery and also engaging with the wheel, said radially-movable parts successively forming means by which one of said rotating members is driven from the other, and also forming means for dividing the spaces between the shell and the wheel into receiving and discharging chambers.
